BED HEADBOARD

Robert H. McMurtrie, Huntingburg, Ind.

Application September 28, 1953, Serial No. 26,971

Term of patent 14 years

(Cl. D5—4)

Fig. 1

Figure 1 is a perspective view of a bed headboard, showing my new design, the bed indicated by dotted lines being for illustrative purpose only; and

I claim:

The ornamental design for a bed headboard, as shown and described.
